FELIX KÄPPLER, OF DRESDEN, GERMANY, ASSIGNOR OF ONE-HALF TO HELEN FRASER, OF LONDON, ENGLAND.

MATCH PLATE AS WELL AS METHOD OF AND MEANS FOR MANUFACTURING THE SAME.

Application filed January 21, 1928, Serial No. 248,526, and in Germany November 30, 1927.

This invention relates in the first place to a match plate having particular configuration and consisting of wood, paste-board, paper, or another suitable material; in the second place it relates to a method of manufacturing said match plates, and in the third place to a machine for carrying said method into practice.

The characteristic features of the match plate consist in this that the matches extend radially from a centre portion with which they are made integral and are connected with said portion only at their feet, so that each of them can be separated from the said portion merely by being torn off the same at its foot. The radial arrangement of the matches renders it possible to combine a particularly large number thereof together, the whole taking up only very little space and permitting convenient housing. Furthermore, the manufacture of match-plates of the kind in question proceeds in a simple and cheap manner, as will appear fully from what follows. The method is carried through with the aid of a suitably designed machine as illustrated diagrammatically and by way of example in the accompanying drawings, in which:

Figure 1 is a side-view of the complete machine, Figure 2 an end view of the device for punching the base-plates out of a blank, this device being that at the left-hand end of Fig. 1 and being drawn to an enlarged scale. Figure 3 is a side-view of the punching device, (as in Fig. 1), Figure 4 a side-view of the device for paraffining the outer halves of the portions projecting radially from the above-mentioned centre-portion and later on forming the matches, this device being in Fig. 1 located about in the middle of the same, shifted somewhat to the right; Figure 5 is a side-view of the device for providing the ends of the radially projecting portions with match heads, this device being located in Fig. 1 at the righthand end of the same; Figure 6 shows details of Fig. 5, Figure 7 is a plan of the parts shown in Fig. 5. Figure 8 is a perspective representation of a match plate or disk, Figure 9 is a plan of means for assembling a large number of the match plates or disks together, with gaps between them, in order to paraffin the outer halves of the radially pro-

jecting parts, and to provide them with heads; Figures 10 and 11 show details of Fig. 9, and Figures 12, 13, 14 and 15 show some other details, all as fully described hereinafter.

The most practical form of the match plates is shown in Fig. 8. This plate resembles a cog-wheel. It is practically circular, but provided with a large number of radial slits by which by far the greatest part of the plate is subdivided into individual radial portions 1^a, except a central portion 1^c having a central hole 1^b. The portions 1^a are to form the matches. The length and breadth of these portions 1^a corresponds to the length and breadth of the usual or normal matches. The "teeth" of the cog-wheel-like plate later on receives the igniting mass. Every portion 1^a can later on, when the match disk has been finished, be torn off the centre portion 1^c and then be used as a match in the usual manner. While in Fig. 8 the match-forming portions increase in breadth radially outwardly, the disk may be so punched out of the blank that every match is of equal breadth from its foot to its head, but then there exist angular gaps between the matches, as will be clear without further explanation. It is also possible to let the radial slits terminate a little from the edge of the plate so that narrow connections remain between the matches at or near their heads; it is then necessary, in order to remove a match from the set of matches, to tear through also the two connections located at or near its head.

The blank from which the match plates or disks are to be punched out consists preferably of a long strip wound on a cylindrical carrier so as to form a roll 1, Fig. 2, which is inserted into the punching machine. The strip is wound off that roll and conducted between pairs of rollers 3/3^a, 4/4^a and 5/5^a by which the paste-board or thick paper is straightened and kept flat between the matrix and the patrinx. The punching machine may be of any suitable design. In the case shown by way of example it is an eccentric press provided with a driving wheel 6 and a fly-wheel 7 which latter is keyed to a shaft 7^a connected with the tool-carrier by two rods 8 guided in the frame of the press and sliding on cam disks 8^a. The tool-carrier is thereby lifted and lowered with such

intervals of time as correspond to the intermittent forward feed of the strip 1.

The three pairs of rollers mentioned are turned intermittently by cog-wheels 10^m/10ⁿ, 5 11^m/11ⁿ and 12 from the shaft 7^a by the intermediary of a cog-wheel 12^a and an intermittently acting gearing consisting of a ratchet-wheel 13 and a pawl 13^a hinged to a crank 14 connected by a rod 15 with 10 another crank 16 affixed to the shaft 7^a.

To each of the shafts of the rollers 3^a, 4^a and 5^a is secured a disk (17, 17^a, 17^b) which is flat or straight on a certain part of its circumference; the circumferential edges of 15 these disks contact with a horizontal bar 19, the ends of which are connected with helical springs extending downwardly and tending continually to draw said bar downwardly and keep it in contact with said disks. The bar 20 19 connects the ends of levers 20 fulcrumed at 20^a to the tool carrier 18 and connected at 20^b with the frame 2 by a rod 20^c. When shortly prior to the downward movement of the tool carrier 18 which carries the punching 25 tool 18^a the bar 19 comes in contact with the flattened portions of the circumference of the disks 17, 17^a and 17^b (which takes place every time after the strip 1 has been fed forward as much as is required for the 30 punching of another set of the match-disks, this feeding movement being effected by means of the intermittently acting gearing 13, 13^a, 14, 15 and 16, and the wheels and rollers connected therewith), the further movement 35 of all members having taken a part in the feed movement of the strip is stopped so that now the punching procedure can take place without any disturbance.

The fly-wheel shaft 7^a is operatively connected by means of cog-wheels 21, 22, 23 and 40 24, to an axle 25 supported in the frame 2 and carrying a cam-disk 26, the circumferential edge of which is in contact with the free end of a double-lever 27 fulcrumed at 28 to the 45 frame 2. The other arm of the lever 27 operates by means of a rod 29 a ratchet-wheel 30 connected with a disk 32 supported at 31 and having in its circumferential surface a large number of holes intended to receive 50 rods 35 having each at its lower end a running wheel 34 and being intended to receive a large number of the punched-out match plates or disks which are arranged in rows upon these rods 35. There is a gap between 55 each two consecutive match plates or disks, the gaps being produced by means of small spacing disks 36, the diameter of which is considerably less than that of the match disks, as appears from Figs. 8 and 11. The 60 number of the match disks and of the spacing disks on one rod 36 amounts to about 100 of each sort of disks.

The transmission ratio of the train of cog-wheels 21, 22, 23, 24 is such that the lever 29 65 which is provided with a projection for ac-

tuating the wheel 30 turns this wheel only an amount corresponding to a fourth, a fifth or a sixth etc. part of the disk 32 (according as this contains 4 or 5 or 6 rods 35) when the rod 35 just acted on is filled with match plates or disks 1^a and spacing disks 36. On the further intermittent movement the next rod 35 which is still without said two sorts of disks passes into the path of the device which pushes the said disks onto the said rods. 75

This device consists, in the first place, of a hopper 37 which is continually supplied with spacing disks 36 by means of an elevator 38, and in the second place of a lever-mechanism 38, 39 which alternately pushes match disks 80 and spacing disks upon the rod 35 now to be provided with both these sorts of disks.

The match disks or plates have been punched out of the blank, it is true, but to start with they remain lying in the plane 85 of the blank or strip of paper or pasteboard and are carried along with it, and pressure must subsequently be applied to them to cause them to leave the strip. This is effected by the lever 10 which is fulcrumed 90 at 10^a on the frame of the punching machine or press and is connected at 10^b with the tool-carrier so that said lever is moved together with, and by, the same. At the moment in which the tool-carrier 18 is 95 moved downwardly, the front arm 11 of said lever, the press-plate 11^a of which lies in the extension of the axis of the rod 35 to be actuated at the time being, presses the match disk just lying below it out of the 100 strip (which now becomes a waste-strip) and the respective match disk passes with its centre hole 1^b upon the respective rod 35 upon which it slides along. Then a spacing disk is put upon the pin. These disks 105 may consist, for instance, of vulcanized fibre, and their thickness may be several times that of the match disks, but their diameter is considerably smaller than that of the match disk, as already mentioned with 110 reference to Figs. 8 and 11, but somewhat larger than the diameter of the hubs of the running wheels 34 and 34^a.

The device for pushing the match-disks out of the discharge tube 37^a of the hopper 37 consists of a pushing member 39 (Figs. 3 and 15) connected by a rod 38 with a crank-pin on the disk 17^b. The front end of the pushing member 39, the horizontal reciprocating movements of which take place upon the table 40, moves along in a slot 37^b of the discharge tube 37^a of the hopper, and a vertical shoulder provided near the end of the member 39 and entering also into said slot 115 engages the edge of the spacing disk which is, at the time being, the lowermost in the discharge tube, the respective spacing disk being now shoved out of this tube through the curved slots 37^c. When the disk leaves the slotted bottom of the discharge tube its 120 125 130

position is such that its centre hole 1^b lies just over one of the rods 35, and it then falls down upon the respective rod and upon the uppermost of the match-disks already 5 present thereon.

In this manner the match plates or disks and the spacing disks are caused to arrive alternately upon the rods 35, and when one of these latter has been filled with them the 10 disk 32 is turned automatically in the already described manner through a certain angle so as to bring the next rod 35 below the discharge tube of the hopper.

Each rod 35 is provided at its lower end 15 with a running wheel 33/34 (Fig. 9), and when a rod has been filled with the two sorts of disks, as described, a running wheel 33^a/34^a is affixed to the upper end of it. The parts 33 and 33^a are the hubs of the wheels 20 34 and 34^a, and there is in each hub a conical bore adapted to receive a correspondingly shaped end of the respective rod 35. The thus finished rod is then withdrawn and placed in horizontal position upon an oblique 25 table 41 provided with grooves in which the wheels 34 and 34^a can roll along. The lower ends of the grooves are closed so that the "rollers" consisting of the filled rods with their running wheels cannot leave 30 the said grooves.

These "rollers" are then conducted singly to the paraffining device (Fig. 4) which consists of a basin 43 into which liquid paraffin is conducted from a receptacle 44 35 through a pipe 45 provided with a cock 46. The supply is controlled by a float (not shown). The basin and the receptacle mentioned are heated by gas-burners supplied with gas through pipes 47 and 48. The 40 waste gases are conducted away through a hood 47.

On both sides of the frame 42 a movable frame adapted to receive the "rollers" mentioned is hinged at 49 and can be lifted vertically either manually or automatically. It is lowered, however, automatically by means of two oblong disks 51 supported at 45 52 and co-operating with rolls carried in bearings 56 affixed to rods 50 also supported 50 at 49 and connected at their other ends by rigid bars with the frame 53. The disks 51 are provided with circumferential grooves 53^a into which the rims of said rolls engage. The disks 51 may be turned or rotated from a shaft 55^a (Fig. 1) by means of a belt or the like, and there may be provided on the frame 42 an engaging and disengaging coupling (not shown) which can be actuated by a pedal 55. The two parallel 55 main members of the frame 53 are provided with grooves corresponding to those in the table 41, and also the distance between them is the same so that the "rollers" (consisting of the rods 35 with the alternating 60 disks) can be transferred from said table to

said frame. The lefthand ends of the said frame members project so far that when the frame 53 is lifted, said ends engage the lowermost "roller" upon the table 41 and lift it out of the table grooves whereby that 70 "roller" runs from the table upon the frame 53, the wheels 34 and 34^a engaging now the grooves in the frame.

The device shown in Fig. 5 is very similar to that shown in Fig. 4, except that there 75 are no gas-burners and no waste-gas hood. The movable members are exactly the same as in Fig. 4, and they have been denoted, therefore, with the same numerals of reference. 57 denotes the stationary frame. Between the two devices is another oblique table 54 over which the match-disk "rollers" 80 pass from the device Fig. 4 to the device Fig. 5. The former serves for paraffining the outer halves of the match-forming portions of the match-disks, the other for providing the match ends with igniting heads. The match-disk "rollers" are transferred from the table to and upon the frame 53 in exactly the same manner as has been described with respect to the table 41 and Fig. 4.

What I am describing in the now following lines is intended for Fig. 4, as well as for Fig. 5. The longitudinal members 53^b 95 of the frame 53 have each a step 53^a, and at the ends of these members is another step 53^c formed by extensions 53^d of the said frame. When a "roller" passes over the steps 53^a it tends, of course, to proceed on its 100 way with an increased speed, but just in this moment or instantly thereafter the frame 53 is lifted a little either manually or automatically so much that the respective "roller" is retained at said steps in that it rolls back 105 against them from the right to the left. In this position the bearings 56 which are open in downward direction engage with their open lower sides or bottom faces the hubs of the running wheels of said "roller" and hold 110 this latter, therefore, fast in its position, and now the pedal 55 is depressed so as to cause the belt or rope driven by the pulley 55^a (Fig. 1) to turn the oblong disks 51. Owing to the shape of these disks the frame 53 is 115 so much lowered that the outer halves of the match-forming portions of the match disks or plates are dipped into the liquid paraffin contained in the basin 43. While the disks 51 are being turned, the rolls held by the open bearings 56 roll along in the circumferential grooves of said disks, and as said rolls are bearing upon the said disk, the frame 50/53 turns downwardly on the pivots 49, in consequence whereof the match-disk 120 "roller" carried by the lower members 50 of this frame sinks so much that the match-portions mentioned can enter into the liquid paraffin, as already described. The match-disks are in rotary motion while their match- 125 130

forming portions pass through the paraffin, and these portions are hereby prevented from getting soaked too strongly with the paraffin.

5 When the oblong disks 51 have made one complete revolution, and the upper rolls have, therefore, arrived again in their uppermost position, as in Fig. 4, the frame 53 (Fig. 4) is lifted to a position corresponding 10 to the position (of the frame 53) shown in dotted lines in Fig. 5. The bearings 56 no longer engage the hubs of the running wheels of the match-disk "roller" lying upon the frame 53, and the respective "roller" can now 15 roll down along the frame 53 to the right-hand end thereof until it arrives at the second step (53^c). There the running wheels pass into the grooves of the frame extensions 53^a in which they are conducted to the 20 grooves of the second oblique table 54 (Fig. 1). These latter grooves are also closed at their lower ends, just as had been described with respect to the table 41, and now the operations described with respect to Fig. 4 are 25 repeated in the device shown in Fig. 5, the only differences being that the basin 43 of this device is not heated and does not contain liquid paraffin but a liquid mass suited for forming the igniting heads at the free ends 30 of the match-portions of the match-disks. This mass is carried upwards by a roller 43^a and transferred in this way to the match ends which are, thus, turned into match heads proper that can be ignited on a suitable rubbing surface. The mass is, of 35 course, of suitable consistency so that a layer of a suitable thickness is carried upwards by and with the roller 43^a, and the frame 53 is only so much lowered that only the ends 40 of the match-forming portions dip into that layer whereby as much remains adhering to said ends as is necessary to form proper match heads. But also while this procedure is going on, the respective match-disk "roller" is kept in rotation, as has been described 45 also with respect to Fig. 4, the rotation being also effected by like means in like manner.

When the production of the igniting heads has been finished, the match "roller" 50 rolls along upon the extensions or rails 53^b/53^c to rails 58 and further to rails 59 carried by a drying frame 60. Abutments are provided at the commencement of the lowermost rails 59^a where the finished "rollers" 55 collect. In this position of the match "rollers" their running wheels contact with each other, but the match-disks do not.

In front of the lowermost rails 59^a a table 60 61 is arranged, the upper surface of which carries a grate 62, the construction of which is shown perspectively in Fig. 13 and in vertical section in Fig. 14. There are in this 65 grate perforations 62^a which receive the rim portions of the disks 1^a, these latter being

therein received in such a position that they are held fast by the oblique edges of said perforations when the rods (after one of the running wheels, the righthand wheel in the example shown, as in Fig. 12) are withdrawn in the direction of the arrow into the position indicated in dotted lines. All spacing disks 36 now fall into a vat 64 connected with the table by an inclined guide-member 70 63. The match-disks remain upon the table 75 and are packed together in equal numbers, say 10, in boxes kept ready for use. The spacing disks collected in the vat 64 are carried away from it by buckets of an elevator 80 38 by which they are conveyed back into the hopper 37 for being used again. The rods freed from the match-disks but having each still one of the running wheels affixed to it are used again in connection with the disk 85 32, as already described.

I claim:

1. A circular match-plate, consisting of a plurality of match-forming members of paper, paste-board, wood or the like which are integral with a base-forming member and 90 are pointed at their free ends and have these ends provided with a head-forming igniting mass, said match-forming members being separated from one another by means of slits in the match plate extending continuously from said base-forming member to the periphery of the disc, so that the match forming members are entirely separate from one another and are only connected at their inner ends to said base-forming member. 95

2. The method of manufacturing match-plates, consisting in feeding forward a strip of paper, paste-board, wood or the like, punching out of it plates consisting each of a plurality of match-forming members 100 which are integral with a base-forming member; moving said strip forward in its plane intermittently and effecting said punching during the periods of rest and carrying the punched-out members forward 105 with the waste portion of the strip during the intermittent movements of the same; pressing the punched-out plates out of the waste strip, assembling them with gaps between them so as to form a sort of roller 110 of them, rotating this roller, moving it while rotating to a paraffin bath, dipping the rims of the rotating plates into this bath, moving the roller further to a pulpy igniting mass, dipping the ends of the match-forming portions of the said roller into this pulp so as to provide said ends with igniting heads, drying these heads, and separating the assembled match plates from one another substantially as set forth. 115

3. The method of manufacturing match-plates, consisting in feeding forward a strip of paper, paste-board, wood or the like, punching out of it plates consisting each of a plurality of match-forming members 120 125 130

- which are integral with a base-forming member; moving said strip forward in its plane intermittently and effecting said punching during the periods of rest and carrying the punched-out members forward with the waste portion of the strip during the intermittent movements of the same; pressing the punched-out plates out of the waste strip, feeding spacing members to 10 said plates from a supply of spacing members, assembling said plates in alternation with said spacing members so as to form a sort of roller of them with gaps between the spacing members, rotating this roller, 15 moving it while rotating to a paraffin bath, dipping the rims of the rotating plates into this bath, moving the roller further to a pulpy igniting mass, dipping the ends of the match-forming portions of the said 20 roller into this pulp so as to provide said ends with igniting heads, drying these heads, and separating the match plates and spacing members from each other, substantially as set forth.
- 25 4. The method of manufacturing match-disks, consisting in intermittently withdrawing portions from a cylindrically wound-up strip of paper, paste-board or the like portions, punching out of it during the periods of rest, disks comprising match-forming members consisting each of a plurality of narrow strips radiating from a central portion by which they are integrally connected; carrying the punched-out disks 30 forward with the waste portion of the strip during the intermittent feed movements; pressing the disks out of said waste portion, feeding to said punched-out disks, spacing disks having a diameter corresponding to that of said central portions from a supply of spacing disks, assembling said punched-out disks in alternation with said spacing disks so as to form a sort of roller of them, rotating this roller, moving it while rotating to a paraffin bath, dipping the rims of the punched-out disks into this bath, moving the roller further to a pulpy igniting mass, dipping the ends of the match-forming portions of the said roller into this pulp so as 40 to provide said ends with igniting heads, drying these heads, and separating the match disks from each other, substantially as set forth.
- 45 5. A machine for the manufacture of match-plates, comprising, in combination, feeding rollers adapted to feed forward a strip of paper, paste-board or the like, and means for turning them intermittently; a plurality of punches adapted to punch out 50 of said strip match plates consisting each of a plurality of match-forming narrow portions connected integrally by a base-forming portion; means for supporting said punched-out portions while the match plates are further conveyed; means for removing the 55 punched-out match-plates from said strip, means for containing a supply of spacing members; means for connecting the match-plates and spacing members with each other, means for transferring said spacing members from said supply to the match plates and for assembling the match plates and spacing members in alternation so as to form a sort of roller; means for conveying the successive rollers to a paraffin bath; 70 means for dipping the rims of the match plate-forming parts of the rollers into said bath; means for conveying the rollers further to a receptacle containing a pulpy igniting mass, and means for dipping the free 75 ends of said plates into this mass; means for drying said match ends, and means for separating the said match-plates, spacing members, and connecting means from each other.
- 80 6. A machine for the manufacture of match-plates, comprising, in combination, an intermittently acting feeding device for a strip of paper, paste-board or the like, a set of punches for punching out of said strip a corresponding plurality of plates each comprising a plurality of match-forming members connected integrally with a common base-forming member; rotary members adapted to actuate the patrices of said 85 punches; a pushing member for discharging said plates from the waste-portion of the strip, and an articulated lever for transmitting motion from said rotary members to said pushing member; and consecutive means 90 for assembling the discharged match-plates axially, dipping the match-forming portions thereof into liquid paraffin on about one half of their length, transmitting the assembled plates to a receptacle containing an igniting 95 pulp, dipping the free ends of said portions into this pulp, and separating the thus finished match-plates proper from each other.
- 100 7. A machine for the manufacture of match-plates, comprising, in combination, an intermittently acting feeding device for a strip of paper, paste-board or the like, a set of punches for punching out of said strip a corresponding plurality of plates each comprising a plurality of match-forming members connected integrally with a common base-forming member; rotary members adapted to actuate the patrices of said 105 punches; a pushing member for discharging said plates from the waste-portion of the strip, and an articulated lever for transmitting motion from said rotary members to said pushing members; means for containing a supply of spacing disks; a set of intermittently turned parallel pins, each being 110 adapted to receive the discharged match-plates and spacing disks in alternation, the diameter of these disks being smaller than that of said plates; means for moving said pins intermittently; means for supplying 115
- 120 125 130

the spacing disks in proper alternation with the match-plates; to said pins and means for conveying the match plates and spacing disks assembled on the pins to a receptacle 5 with liquid paraffin, dipping the match-forming portions of the said plates into the paraffin for about one half of their length, transferring the assembled plates to a receptacle containing an igniting pulp, dipping 10 the free ends of said portions into this pulp, and separating the thus finished match-plates proper from each other.

8. A machine for the manufacture of match-plates, comprising, in combination an 15 intermittently acting feeding device for a strip of paper, paste-board or the like, a set of punches for punching out of said strip a corresponding plurality of plates each comprising a plurality of match-forming members 20 connected integrally with a common base-forming member; rotary members adapted to actuate the patrices of said punches; a pushing member for discharging said plates from the waste-portion of the 25 strip, and an articulated lever for transmitting motion from said rotary members to said pushing members; means for containing a supply of spacing disks; a set of intermittently turned parallel pins, each being 30 adapted to receive the discharged match-plates and spacing disks in alternation, the diameter of these disks being smaller than that of said plates; means for moving said pins intermittently; means for supplying 35 the spacing disks in proper alternation with the match-plates to said pins; a running-wheel attached to the lower end of each of said pins, and a detachable running-wheel attached to the upper end of each pin after 40 this latter has been filled with the alternating disks; means for conveying the filled pins on their wheels to a receptacle with liquid paraffin, dipping the match-forming portions of the said plates into the paraffin for 45 about one half of their length, transmitting the assembled plates to a receptacle containing an igniting pulp, dipping the free ends of said portions into this pulp, and separating the thus finished match-plates proper 50 from each other.

9. A machine for the manufacture of match-plates, comprising, in combination, an intermittently acting feeding device for a strip of paper, paste-board or the like, a 55 set of punches for punching out of said strip a corresponding plurality of plates each comprising a plurality of match-forming members connected integrally with a common base-forming member; rotary members 60 adapted to actuate the patrices of said punches; a pushing member for discharging said plates from the waste-portion of the strip, and an articulated lever for transmitting motion from said rotary members to 65 said pushing member; and consecutive means

for assembling the discharged match-plates axially, a basin and a receptacle containing liquid paraffin, means for heating said basin and said receptacle, means for conveying the assembled match-plates to the said basin and 70 for dipping the match-forming portions of the said plates into the paraffin for about one half of their length, transmitting the assembled plates to a receptacle containing an igniting pulp, dipping the free ends 75 of said portions into this pulp, and separating the thus finished match-plates proper from each other.

10. A machine for the manufacture of match-plates, comprising, in combination, an intermittently acting feeding device for a strip of paper, paste-board or the like, a set of punches for punching out of said strip a corresponding plurality of plates each comprising a plurality of match-forming members connected integrally with a common base-forming member; rotary members 80 adapted to actuate the patrices of said punches; a pushing member for discharging said plates from the waste-portion of the strip, and an articulated lever for transmitting motion from said rotary members to said pushing members; means for containing a supply of spacing discs, a set of intermittently turned parallel pins, each being 85 adapted to receive the discharged match-plates and spacing disks in alternation, the diameter of these disks being smaller than that of said plates; means for moving said pins intermittently; means for supplying 90 the spacing disks in proper alternation with the match-plates to said pins; a running-wheel attached to the lower end of each of said pins, and a detachable running-wheel attached to the upper end of each pin after 95 this latter has been filled with the alternating disks; two sets of stationary rails having stepped surfaces adapted to serve partly as supports for the running-wheels of the match-disk carrying pins, and partly as 100 supports for the hubs of said wheels; oscillable rails connecting said sets of stationary rails with each other; means for conveying the match plates and spacing disks assembled on the pins to a receptacle with 105 liquid paraffin; oblong disks located above this receptacle and receiving the filled pins one after the other; means for rotating said oblong disk so as to dip the match-forming portions of the match-disks into the paraffin for about one half of their length, transmitting the assembled plates to a receptacle containing an igniting pulp, dipping the free ends of said portions into this pulp, and separating the thus finished match-110 plates proper from each other.

11. A machine for the manufacture of match-plates, comprising, in combination, an intermittently acting feeding device for a strip of paper, paste-board or the like, a 115

set of punches for punching out of said strip a corresponding plurality of plates each comprising a plurality of match-forming members connected integrally with a common base-forming member; rotary members adapted to actuate the patrices of said punches; a pushing member for discharging said plates from the waste-portion of the strip, and an articulated lever for transmitting motion from said rotary members to said pushing member; and consecutive means for assembling the discharged match-plates axially, dipping the match-forming portions thereof into liquid paraffin on about one half of their length, transmitting the assembled plates to a receptacle containing an igniting pulp; oblong disks located above this receptacle and receiving the filled pins one after the other; means for rotating said oblong disks so as to dip the match-forming portions of the match-disks with their ends into the pulp so as to provide these ends with igniting heads; means for drying these heads and means for detaching the match-disks and the spacing disks from the pin upon which they have been assembled.

12. A machine for the manufacture of match-plates, comprising, in combination, an intermittently acting feeding device for a strip of paper, paste-board or the like, a set of punches for punching out of said strip a corresponding plurality of plates each comprising a plurality of match-forming

members connected integrally with a common base-forming member; rotary members adapted to actuate the patrices of said punches; a pushing member for discharging said plates from the waste-portion of the strip, and an articulated lever for transmitting motion from said rotary members to said pushing members; a set of intermittently turned parallel pins, each being adapted to receive the discharged match-plates and spacing disks in alternation, the diameter of these disks being smaller than that of said plates; means for moving said pins intermittently; means for supplying the spacing disks in proper alternation with the match-plates to said pins; and means for conveying the match plates and spacing disks assembled on the pins to a receptacle with liquid paraffin, dipping the match-forming portions of the said plates into the paraffin for about one half of their length, transmitting the assembled plates to a receptacle containing an igniting pulp, dipping the free ends of said portions into this pulp; a grate-like table having slots through which the spacing disks can fall when the pins having carried them and the match-disks up to then are withdrawn; an inclined guide member receiving the spacing disks, and means for conveying them back to the place where they have been used initially, substantially as set forth.

In testimony whereof I affix my signature
FELIX KÄPPLER.
